UNITED STATES PATENT OFFICE.

CHARLES P. McFARLAND, OF BEVERLY HILLS, AND WALTER E. RANDALL, OF LOS ANGELES, CALIFORNIA.

DESIGN FOR A VENDING-MACHINE CASING.

Application filed June 17, 1926. Serial No. 18,079. Term of patent 14 years.

To all whom it may concern:

Be it known that we, CHARLES P. McFARLAND and WALTER E. RANDALL, both citizens of the United States, the former residing at Beverly Hills, in the county of Los Angeles and State of California, and the latter residing at Los Angeles, in the county of Los Angeles and State of California, have invented a new, original, and ornamental Design for Vending-Machine Casing, of which the following is a specification, reference

being had to the accompanying drawing, forming part thereof.

In the drawing, the figure represents a perspective view of the vending machine casing showing my new design.

I claim:

The ornamental design for a vending machine casing, as shown.

CHARLES P. McFARLAND.
WALTER E. RANDALL.
